UNITED STATES PATENT OFFICE.

WILLIAM H. BROWN, OF CLEVELAND, OHIO, ASSIGNOR TO DRYDEN RUBBER COMPANY,
A CORPORATION OF ILLINOIS.

MACHINE FOR PLACING WASHERS ON UPSTANDING PINS.

Application filed August 24, 1925. Serial No. 52,146.

This invention relates to mechanism for threading washers on upstanding pins supported on a plate, and its special purpose is to provide means for placing convex washers on rows of upstanding pins affixed to the bottom-plate of a multiple rubber-heel mold, as more particularly hereinafter set forth.

In the drawings annexed—

Fig. 1 is a front elevation of my apparatus:

Fig. 2 is a side elevation thereof;

Fig. 3 is a plan view thereof;

Fig. 4 is a vertical sectional view taken through the hopper:

15 Figs. 5 and 6 are detail views hereinafter described:

Fig. 7 is a detail view of the mechanism for charging the magazine channels;

Figs. 8 and 9 are detail views of the dam of the bank of magazine channels;

Fig. 10 is a view partly in vertical section showing the agitator mechanism;

25 Figs. 11, 12, 13 and 14 are views of other details of the mechanism hereinafter specifically described;

Figs. 15 to 24 are detail views of the portable washer-threader.

On an elevated base-board 20, I mount a standard 21, and on this standard I mount a stationary horizontal shaft 22 on which the tumbler-barrel 23 is journaled, this barrel having a closed rear end to which is affixed a worm-gear 24 which is driven by a worm 25, which worm, in turn, is driven, in the present instance, by an electric motor 26 mounted on the base 20. This mechanism serves to rotate the tumbler 23 continuously.

The forward open face of the tumbler is covered by a plate 27 which, in the present instance, is made of glass to permit a clear view of the operations taking place behind the glass. This glass plate 27 is bolted to a vertical metal plate 28 by means of bolts 29 and is arranged to have frictional contact with the front cylindrical edge of the tumbler-barrel. The plate 28 is rigidly supported on the base 20, and it is provided with a circular hole through which the front end of the tumbler-barrel projects in order to have direct contact with the face of the glass plate. The forward end of the stationary shaft 22 extends through a hole in the glass plate and a nut 30 is tapped on to the end of the shaft for the purpose of holding the glass plate in proper place. A funnel 31 is fas-

tened to the face of the glass plate and has a tubular extension 32 which passes through a hole in the glass plate for the purpose of delivering the washers into the tumbler-barrel.

As will be seen particularly in Fig. 7, the rotation of the tumbler in the direction indicated by the arrow delivers the washers 33 into an annular channel 34 formed around the right-hand edge of the tumbler-barrel by means of a strip 35 clamped between the glass plate and the metal plate 28. The washers gravitate down this channel 34 into an oblique channel 36 formed by a strip 37 and the upper ends of strips 38, these strips 38 forming a plurality of five vertical channels 39, the top edges of the strips 38 being bevelled off downwardly to the left to permit the washers to roll by gravity past the tops of all the channels except the last one, i. e., the one at the left. All these strips 38 and 37 are clamped between the glass plate and the metal supporting plate 28.

The lower end of the channels 39 deliver the washers into a series of flat metal tubes 40 each of which is open along its front face for the purpose of enabling the attendant to inspect the columns of washers that are delivered thereinto by the channels or chutes 39. There is one tube 40 for each channel 39, and all the tubes are suitably spaced with respect to each other to preserve their parallelism. They desirably incline downwardly toward the right-hand, in the same direction as the receiving-channels 39. The lower ends of these channels 40 are temporarily closed by means of a series of fingers 41 which are adapted to be manually moved from operative position at the will of the operator, as more fully hereinafter set forth. The washers, as they run down the channel 36, drop into the channels 39 and thence into the tubes 40, coming to rest against the stop-fingers 41. When all the channels are filled, the washers stop rolling into the feed-channel 36, but, of course, the tumbler will continue to rotate. The momentum the rolling washers receive in running down the channel 34 will carry them to the far end of the feed-channel 36, so that the far channel 40 will usually fill before the others; after this channel fills, the others will fill in succession. In the drawings, Fig. 7, the far channel is filled and the next channel is nearly filled. After

2

a previous channel is filled, a washer lodges on the top of the adjacent division-strip 38 and thus serves to guide the succeeding washers into the next adjacent channel. In 5 order to give the washers sufficient gravity momentum to be carried quickly to the far end of the inclined channel 36, I arrange the point of delivery from the tumbler into the channel 34 as far to the right of the entrance to channel 34 as practicable. To accomplish this, I provide a metal strip 42 and extend it up along the entrance-side of the channel 34, as shown in Fig. 7. The washers roll up the inner face of this strip 10 42 and drop off its end into the channel 34 at a point far enough up to give the washers the necessary momentum. This strip 42 is desirably affixed to a strip 43, clamped between the glass and the metal plate 28 and 15 extending around the edge of the tumbler to close the space between the same and the glass sheet. The washers roll along the inside of this strip 43 until they drop off the end of the extension member 42. All the 20 strips 35, 38 and 43 are desirably affixed to the metal plate 28 and have their front faces smoothed off so that when the glass plate is bolted up it will fit close against the faces of the strips.

- 30 To insure against any of the washers sticking or lodging on the way down the inclined distributing-channel 36, I provide the following dislodging or agitating devices: At the upper end of each of the division-strips 38, I provide a transverse pin 44 which is carried by a bar 45 arranged on the rear side of the supporting-plate 28, the pins working through slots in said plate 28. This bar 45 is reciprocated endwise so as 35 to move the pins 44, back and forth, part-way across the upper ends of the channels 39. The means for causing this action of the bar 45 consists of a plurality of radial pins or knobs 46 affixed to the exterior of the 40 tumbler and arranged to work against the cam-face 47 of the bar 45. The bar 45 is affixed to the plate 28 by means of screws 48 48 anchored in the plate 28 and working through slots 49 in the bar, a spring 50 being employed to normally hold the bar 45 in its down position to thus hold the pins 44 back, out of the channels 39. The rotation of the tumbler-barrel 23 gives this bar 45 a comparatively rapid movement back 55 and forth, thus keeping the pins 44 moving rapidly back and forth partially across the channels 39, the location of these pins in the channels being such that as the washers roll across each channel they will strike one of 60 these pins. In this way, lodgment of the washers against the top ends of the division-strips 38 is absolutely prevented. At the far end of the channel 36 there is provided two additional agitator-pins 44' for the purpose of insuring agitation of any washers 65

that might accumulate, in abutting relation in the distributing-channel 36. The tumbler-barrel 23 is desirably provided with perforations 51 for the purpose of discharging the foreign matters that might get into 70 the barrel.

For the purpose of agitating the washers as the barrel rotates, I desirably provide the interior of the barrel with a plurality of curved ribs 52 arranged near the forward 75 edge of the barrel in such manner as to assist in not only tumbling the washers about in the barrel but also in causing them to travel toward the front edge of the barrel, whence they are delivered into the distributing-channel hereinbefore described. The washers gravitate into the radial notches 53 formed in the edge of the barrel and thence down between radial ribs 54 affixed to or 80 formed on the edge of the barrel in such position as to wipe the inner face of the glass plate as the barrel rotates. As the barrel rotates, the washers drop out of the radial channels formed by the ribs 54 into the 85 curved receiving-channel 34, whence they, as 90 described, roll down into the distributing-channel 36. When convex washers are used, as in the present instance, it is essential that they be delivered into the channel 34 with their convex sides facing all in one direction, 95 inwardly in the present instance. I insure this by so shaping the radial channels between the ribs 54 as to prevent any washer that lodges in the notch 53 from passing down through said channel unless the convex side faces inwardly. This is shown more particularly in Fig. 6, which shows the 100 lower washer 33 in position to pass on into the distributing-channel, while the upper washer 33' is turned with the convex side outwardly and therefore cannot pass down through the channel. For this purpose, the channel is centrally dished or deepened at 55, so that unless the convex side of the washer is turned inwardly, the washer cannot fall down through the channel and will 105 therefore be carried up and tumbled back into the barrel. At the proper speed of rotation of the barrel, enough of the washers will be turned in the proper direction for 110 delivery to keep practically a continuous supply of washers running into the distributing-channel 36. For the purpose of insuring the feed of the washers toward the 115 delivery-channels in the edge of the barrel, the interior of the barrel is tapered backwardly to thus provide an inclined surface extending downwardly and forwardly. It will be understood that the strip 43, Fig. 7, 120 extends around the edge of the barrel and closes all the delivery-channels therein except that on the ascending side of the barrel, where a sufficient number of the channels are left uncovered to permit the washers to 125 roll out into the receiving-channel 34. 130

The length of the magazine channels 40 is such that when the lowermost row of washers rests upon the stops 41, the topmost washer in each channel will have its upper edge about in line with the top edges of the division-strips 38, so that the filling of one of the right-hand magazine channels 39 before the others would not interfere with the subsequent filling of the others. It sometimes happens, however, that one or more of the washers in the lowest row gets its lower edge beyond the ends of the fingers; when this occurs, it sometimes interferes with the proper filling of all the magazines, so that I have provided means for straightening the lower row of washers. For this purpose, I provide a supplemental set of stop-fingers 56 pivotally mounted at a point above the main fingers 41, in such position as to be manually pressed into engagement with the row of washers just above the last row, a spring 59 being provided to throw these fingers off the washers as soon as they are manually released. When the attendant desires to level off the last row of washers, he first clamps the second-to-the-last row of washers by means of the fingers 56; then he releases fingers 41, thereby permitting the lowest row of washers to drop out of the tubes; then he lets fingers 41 go back to closing position; then he releases supplemental fingers 56 and thereby permits all the columns of washers to descend until the lowest row, which has been held up by the temporary fingers 56, falls into abutting relation with the fingers 41.

Any suitable mechanism may be employed for mounting and operating the stop-fingers 41 and 56. I have shown the fingers 41 pivoted at 58, a spring 57 being employed for normally forcing these fingers into action and a stop 60 being employed to restrict the outward movement of the upper end of the plate 61, carrying the fingers 41. A plate 62 carrying the fingers 56 is pivoted at 63, on the side wings of plate 61, the aforesaid spring 59 serving to swing the upper end of this plate 62 toward the tubes and thus hold the fingers out of action.

After the washers have been deposited in the main magazine tubes 40 hereinbefore described, they remain there until they are removed en masse into a vertical, detachable magazine designated as a whole by the numeral 64, which consists of a plurality of tubes 65 equal in number and cross-sectional shape to the tubes 40. They are, like tubes 40, mounted side by side, so that their upper, open, inlet-ends may be adjusted into alignment with the open, lower ends of the tubes 40, as shown in dotted lines in Figs. 8 and 9. This exact alinement of the tubes is obtained by a plate 66 rigidly supported on a frame member 67 and provided with side flanges 68, forming a trough in which the lower ends

of the tubes 40 lie, the wings 68 being provided with inwardly-extending pins 69 which together with the back plate 66 serve to guide and hold the ends of the tubes 65 in proper position with respect to the main magazine tubes, so that when the stop-fingers 41 are shifted to release position, the washers in the main columns will simultaneously drop by gravity into the tubes 65 of the portable magazine.

The portable magazine is held up in position to receive washers by the following means: A swinging yoke 70 is pivotally mounted on a pin 71 supported by a frame member 72, the free ends of the yoke being provided with notches 73 and a spring 74 being employed to normally swing the notched ends upwardly. The lower end of the portable magazine is provided with a pair of oppositely-projecting lateral pins 75 which are adapted to rest in notches 73, as shown in Fig. 11. With this mechanism, the spring 74 will force the pins 75 upwardly with sufficient power to hold the detachable magazine in position while the washers are transferring themselves into the detachable magazine. When the detachable magazine is filled, the operator releases the stop-fingers 41 to allow them to go into operative position, and then removes the portable magazine by simply depressing it far enough to disconnect the upper ends of its tubes from the guide-plate 66-68.

The detachable magazine is provided with mechanism whereby, by manually moving it along, over rows of pins in the mold-plate, the pins will automatically withdraw the washers, one by one, from the tubes 65. This mechanism is constructed as follows: A tube-like frame 76 is attached to the lower ends 105 of the tubes 65, just in front of the tubes, by means of a series of brackets 78 whose forwardly-projecting horizontal members lie upon the top face of the tube-frame 76 and are pivotally connected thereto by vertical 110 pivots 79. The lower ends of tubes 65 extend down behind the frame 76 and are curved rearwardly, the extreme lower end of each tube being fastened to the forward ends of the arms 80 of a fork which is pivotally mounted on the lower ends of the aforesaid pivots 79, so that each of these forks 80 has a pivotal action on the same axis as the brackets 78. The ends of the forks curve upwardly at their forward, pivoted 120 ends, so that the slot or bifurcation forming the forks will present an open arch 81 facing forwardly.

The lower end of each of the tubes 65 is normally closed by a spring finger 82 affixed at its upper end to the tube 65 and having its lower end shouldered to enter the channel of the tube, at the point where it connects with the forks 80, said shoulders (83) resting on top of the back-turned ends 125 130

of the tubes. This finger is provided with a longitudinal notch 84 and the lower end of the tube is also notched at 85, these notches being provided for the purpose of permitting the pins on the mold-plate to pass through between the arms of the fork 80. The frame member 76 is mounted on a pair of runners 86 arranged outside of the lower ends of the tubes 65. A guide bar 87 is fastened to the under side of the frame member 76 in position to pass along between two adjacent rows of the pins of the mold-plate and thus guide the mechanism as it is moved along by the attendant.

In using this portable appliance to thread the washers on the pins, this appliance is manually moved across the mold-plate with the lower edges of the runners 86 resting on the upper face thereof and the guide-plate 87 running along between two adjacent rows of pins. The guide-plate and the runners will be so positioned that as the device is moved along the mold-plate, the several rows of pins thereon will pass into the arches 81 and then out through the rear ends of the forks. As each pin passes along under its tube 65, it will engage in a hole in the washer, as shown particularly in Fig. 23, and snap the same off the rear end of the tube and fork, the spring 82 yielding sufficiently to permit this to be done. The parts are so constructed that the lowermost washer in each tube is presented in an inclined position, as shown in Fig. 23, so that the upper end of the pin will engage the hole in the washer, as stated, and thus, as the device moves along, snap the washer away from the spring in the fork; and as each washer is snapped off the next washer drops into place to be in turn picked off by the next pin in that row.

For one reason or another, the pins in the mold-plate are not always in exact alignment, hence it is desirable that means be provided whereby the washer-delivering devices shall be capable of automatic lateral adjustment. This is provided for by the pivoting of the forks 80 and the brackets 78 on the frame, by means of the pivots 79. With this pivotal arrangement, it will be seen that when the fork 80 encounters a pin slightly bent or out of alignment to the remaining pins, the fork may yield laterally, in either direction, to accommodate such pin. The tubes 65 are connected together at their upper ends by a cross-bar or plate 88. This does not hinder the proper operation of these pivotal connections, as the tubes are of sufficiently thin metal and of sufficient length to yield torsionally to a sufficient degree to permit the comparatively slight lateral movements of the forks that are required.

A guard plate 89 is positioned to the rear and just above the rear ends of the deliv-

ery forks 80, this guard plate being supported by means of arms 90 attached to the frame 76, in position to pass just over the top ends of the mold-pins. The object of this is to prevent the washers jouncing off the pins after they are placed thereon. As the device moves along, the guard plate passes over the top ends of the transverse row of pins immediately after the washers are deposited thereon, thus preventing the washers flopping off the pins, thereby enabling the operator to move the threading apparatus across the mold-plate with considerable speed.

It is desirable that the runners 86 shall be vertically adjustable with reference to the frame member 76 in order that the apparatus may be adapted for mold-pins of different heights. I accomplish this adjustment in the following manner: Attached to the runners and rigidly connecting them is a yoke 91 which lies within the tubular frame 76 and is connected with the top wall thereof by means of a clamp screw 92, whose upper threaded end extends up through a slot 93 in the top wall of the frame member, a clamp-nut 94 being provided to draw the yoke-member and the adjacent wall of the frame toward each other. By tightening the thumb-nut 94, it will be seen that the frame member is clamped hard against the upper edges of the runners, thus providing for a rigid frame structure. The upper edges of the runners enter transverse slits 95 formed in the frame member and the upper edges of the runners are each provided with a pair of stepped abutments 96. In Fig. 21, the adjustment is the lowest obtainable with the present construction. For longer mold-pins, the thumb-nut 94 will be loosened and the runners will be adjusted to bring into use higher pairs of steps 96.

As will be seen from Fig. 18, the left-hand one of the tubes 65 is in reality a supplemental tube in that it is so constructed as to deliver its charge of washers into the adjacent one of the tubes, the lower end of the channel, at 97 being turned downwardly and merged with the channel of the adjacent tube. The purpose of this supplemental tube is to supply an extra number of washers to said adjacent tube. The need for this is due to the fact that in the heel molds now in general use, one row of the pins contains more pins than the other rows, thereby necessitating a larger number of washers for the tube that supplies that row of pins. In use of the device, when the washers in the main tube are discharged to a point below the junction with the supplemental tube, the attendant brings the supplemental tube into communication with its adjacent tube by swinging over a little gate 98 pivoted at the junction of the channels

to thus permit the washers in the supplemental tube to gravitate into the main tube. This gate 98 is mounted on a plate 99 pivotally supported at 100 so that the gate 5 may be shifted to either position by edge-wisely moving the lower end of the plate 99. This plate is desirably made of glass to permit the attendant to watch the movement of the washers in the channel. The 10 gate-carrying plate 99 is limited in its movements by means of a bolt 101 mounted on a plate or bar connecting the two adjacent tubes, the plate 99 being provided with a slot 102 to permit limited movement of the plate. The pivot 100 is mounted on a 15 bar 103 which connects the supplemental tube to its main tube. The plate 88 heretofore described also connects the supplemental tube with its main tube. This plate 20 88 is slightly resilient to form a sort of pivotal connection between the two left side tubes and the remainder of the bank of tubes, this being desirable in order to facilitate the pivotal action of the fork 80 which 25 is connected to this pair of tubes.

I have shown the base 20 supported on a tripod frame and the magazine support consists of a tubular rod depending from the upper end of said frame. This frame arrangement is merely for illustrative purposes, it being obvious that any suitable arrangement of frame structure may be employed. In fact, it may be desirable in some instances to mount the apparatus on a 30 trolley line so that it may be shifted about from one set of molds to another set. The rapidity with which the main magazine is refilled and the quickness and ease with which a charge of washers may be transferred to the portable magazine renders it possible for this apparatus to be used to supply a large number of molds, hence, as stated, it may be desirable in some instances to provide means for readily shifting the apparatus from point to point in the shop in order to reduce the time of the attendant in getting the portable magazine recharged. I have shown a swinging trough 104 normally suspended underneath the main magazine tubes 40 to catch any washers that may fall out of the tubes when the portable magazine tube 65 is not in position. This trough is so supported that when the portable tubes are put in position, the trough will be thereby moved to one side out of the way. A bucket 105 may be supported at the delivery-end of the trough to receive the washers that drop into the trough.

It is obvious that in some case I may do 60 away with the set of magazine tubes 40 and deliver the washers directly into the portable magazine from the channels 39; in this case, however, it will of course be necessary to leave the portable magazine attached a sufficient length of time to permit the washers

feed singly into the tubes 65, just as the run into the channels 39.

What I claim as new is:

1. In a machine of the class set forth, a rotary tumbler-barrel having around its 70 edge a series of inclined notches leading into a series of radial channels, these channels being centrally deepened, a closure-plate for the open end of the tumbler-barrel, and a receiving-channel arranged in juxtaposition 75 to the aforesaid radial channels.

2. In a machine of the class set forth, a rotary tumbling barrel having delivery channels at the edge of its open end, a closure-plate for said open end, a stationary plate 80 attached to said closure-plate, a receiving-channel between said plates connected to a downwardly-extending discharging-channel between the plates, and a plurality of receiving-channels connected at different 85 points to said distributing-channel.

3. In a machine of the class set forth, a rotary tumbler having washer-delivering channels in its edge, a wall closing said channels except on the ascending side of said 90 tumbler, a curved receiving channel adjacent said ascending side, a distributing channel connected to the delivery end of said receiving-channel and extending downwardly therefrom, and a plurality of magazine-95 channels connected at different points along said discharging-channel, for the purposes set forth.

4. In a machine of the class set forth, a receiving-channel and means for delivering 100 washers edgewisely thereinto, a downwardly-inclined distributing-channel connected to the exit-end of said receiving-channel, a plurality of magazine-channels connected at 105 points along said distributing channel, and means at the upper end of each one of said magazine-channels for agitating the washers as they come down the distributing-channel.

5. In a machine of the class set forth, a receiving-channel and means for delivering 110 washers edgewisely thereinto, a downwardly-inclined distributing-channel connected to the exit-end of said receiving-channel, a plurality of magazine-channels connected at points along said distributing-channel, and means at the upper end of each one of said magazine-channels for agitating the washers as they come down the distributing-channel, said agitating means 115 consisting of a vibratory pin adapted to move back and forth across a portion of each magazine-channel.

6. In a machine of the class set forth, a receiving-channel and means for delivering 125 washers edgewisely thereinto, a downwardly-inclined distributing-channel connected to the exit-end of said receiving-channel, a plurality of magazine-channels connected at points along said distributing-channel, and means at the upper end of each one of said 130

magazine-channels for agitating the washers as they come down the distributing-channel, said agitating means consisting of a vibratory pin adapted to move back and forth across a portion of each magazine-channel, means being provided whereby the mechanism for delivering the washers into the receiving-channel causes the vibratory action of said pin.

7. In a machine of the class set forth, a receiving-channel and means for delivering washers edgewisely thereinto, a downwardly-inclined distributing-channel connected to the exit-end of said receiving-channel, a plurality of magazine-channels connected at points along said distributing-channel, and means at the upper end of each one of said magazine-channels for agitating the washers as they come down the distributing-channel, said agitating means embodying pins and mechanism for vibrating said pins partially across the far sides of said magazine-channels at the extreme upper ends thereof.

8. In a machine of the class set forth, a receiving-channel and means for delivering washers edgewisely thereinto, a downwardly-inclined distributing-channel connected to the exit-end of said receiving-channel, a plurality of magazine-channels connected at points along said distributing-channel, and means at the upper end of each one of said magazine-channels for agitating the washers as they come down the distributing-channel, said agitating means including means at the extreme lower end of the distributing-channel, adjacent the last one of the magazine-channels, for agitating the washer which rests at the top end of the last column of washers in the magazine.

9. In a machine of the class set forth, a plurality of magazine-tubes and means for delivering washers into the upper ends thereof, and means at the lower ends of the magazine-tubes for temporarily arresting the several columns of washers, this arresting means being manually operable whereby at the will of the operator the entire bank of magazine-tubes may be discharged.

10. In a machine of the class set forth, a plurality of magazine-tubes and means for delivering washers into the upper ends thereof, and means at the lower ends of the magazine-tubes for temporarily arresting the several columns of washers, this arresting means being manually operable whereby at the will of the operator the entire bank of magazine-tubes may be discharged, said arresting means embodying a series of fingers carried by a single member whereby the fingers may be simultaneously actuated.

11. In a machine of the class set forth, a plurality of magazine-tubes and means for charging the same with washers gravitatingly superposed therein, a main arresting means at the ends of the columns of washers,

and a supplemental arresting means adapted to engage a row of washers above the lowermost row, for the purpose set forth.

12. In a machine of the class set forth, a plurality of magazine-tubes and means for charging the same with washers gravitatingly superposed therein, a main arresting means at the ends of the columns of washers, and a supplemental arresting means adapted to engage a row of washers above the lowermost row, means being provided whereby the main arresting means is manually operable independently of the manually-operable supplemental arresting means.

13. In combination with a plurality of magazine-tubes in which the washers are gravitatingly superposed in the tubes, a set of main arresting fingers at the lower ends of the tubes adapted to engage under the lowermost row of washers therein, a supplemental set of arresting fingers adapted to engage a row of washers above the lowermost row, and means whereby each set of fingers may be manually operated independently of the other set.

14. In combination with a main magazine and means for filling the tubes thereof with washers, and a portable magazine detachably connected to said main magazine, means for discharging the contents of the main magazine into the portable magazine, and means on the portable magazine for threading the washers one by one onto mold-pins.

15. In combination with a main magazine embodying a plurality of magazine-tubes, a portable detachable magazine embodying a similar bank of tubes, means for detachably and resiliently holding the tubes of the portable magazine in abutting relation to the tubes of the main magazine, and means for releasing the charges of washers of the main magazine and permitting them to gravitate into the corresponding tubes of the portable magazine.

16. In combination with a main magazine embodying tubes, a portable magazine embodying a similar series of tubes and carrying a threading mechanism at its lower end, and means for detachably holding the portable magazine in position to receive the washers from the main magazine, this means embodying a swinging spring-actuated yoke having notches engaging pins carried by the portable magazine.

17. A portable magazine having a plurality of magazine tubes in which the washers are superposed gravitatingly, a runner-carrying frame supporting said tubes, and means whereby the mold-pins pick the washers one-by-one out of the lower ends of the tubes, means being provided whereby the frame and the runners are vertically adjustable with respect to each other to adapt the magazine for pins of different heights.

18. A portable magazine having a plural-

- ity of magazine tubes in which the washers are superposed gravitatingly, a runner-carrying frame supporting said tubes, and means whereby the mold-pins pick the washers one-by-one out of the lower ends of said tubes, means being provided whereby the frame and the runners are vertically adjustable with respect to each other to adapt the mechanism for pins of different heights, 5
- 10 said means embodying stepped upper edges on the runners and devices for clamping the frame against any pair of said steps.
19. A portable magazine embodying a frame, a pair of separated runners carried by said frame, a plurality of washer-tubes pivotally mounted on said frame, a fork for each tube pivotally mounted on said frame and connected to the lower end of its tube, means being provided whereby the washers 15
- 20 will be picked off one-by-one by the mold-pins as they pass through said fork.
20. A portable washer-threader embodying a frame, a pair of runners mounted thereon, a plurality of washer magazine tubes pivotally mounted on the frame and 25
- curving downwardly and backwardly at their lower ends, a fork for each tube pivotally mounted at its forward end on the frame and curving downwardly and backwardly and attached to the lower end of its 30 companion tube, means being provided whereby as each fork passes along over its row of mold-pins, the washers will be picked off by the pins one-by-one.
21. A portable magazine having a plural- 35 ity of washer magazine tubes in which the washers are superposed gravitatingly, a runner-carrying frame supporting said tubes, and means whereby mold-pins pick the washers one-by-one out of the lower ends 40 of said tubes, said means embodying a fork attached to each tube and pivotally connected at its forward end to said frame, the lower end of each tube being laterally movable to permit it to laterally swing with its 45 fork.

In testimony whereof I hereunto affix my signature.

WILLIAM H. BROWN.
